(57) **CLAIM**

The ornamental design for an automotive safety device, as shown and described.

DESCRIPTION

This application is related to U.S. Design patent application Ser. No. 29/435,766, entitled Automotive Safety Device, filed Oct. 28, 2013.

FIG. 1 is a perspective view of an automotive safety device showing my new design in a closed configuration, according to an embodiment of the invention;

FIG. 2 is a right side elevational view of the automotive safety device of FIG. 1;

FIG. 3 is a top view of the automotive safety device of FIG. 1; FIG. 4 is a bottom view of the automotive safety device of FIG. 1;

FIG. 5 is a rear elevational view of the automotive safety device of FIG. 1;

FIG. 6 is a front elevational view of the automotive safety device of FIG. 1;

FIG. 7 is a perspective view of the automotive safety device of FIG. 1, shown in an open configuration;

FIG. 8 is a right side elevational view of the automotive safety device of FIG. 7;

FIG. 9 is a top view of the automotive safety device of FIG. 7;

FIG. 10 is a bottom view of the automotive safety device of FIG. 7;

FIG. 11 is a rear elevational view of the automotive safety device of FIG. 7; and,

FIG. 12 is a front elevational view of the automotive safety device of FIG. 7.

The matter shown in dashed lines is environmental structure and forms no part of the claimed design.
